UNITED STATES PATENT OFFICE.

ARTHUR TREVOR DAWSON AND GEORGE THOMAS BUCKHAM, OF LONDON, ENGLAND, ASSIGNORS TO VICKERS SONS & MAXIM, LIMITED, OF WESTMINSTER, ENGLAND.

ELEVATING, TRAVERSING, AND SIGHTING APPARATUS FOR FIELD-GUNS.

SPECIFICATION forming part of Letters Patent No. 743,255, dated November 3, 1903.

Application filed June 1, 1903. Serial No. 159,612. (No model.)

To all whom it may concern:

Be it known that we, ARTHUR TREVOR DAWSON, lieutenant of the Royal Navy, director and superintendent of Ordnance Works, and GEORGE THOMAS BUCKHAM, engineer, both subjects of the King of Great Britain, residing at 32 Victoria street, Westminster, in the county of London, England, have invented certain new and useful Improvements Relating to the Elevating, Traversing, and Sighting Apparatus of Field-Guns, of which the following is a specification.

This invention has reference to the elevating, traversing, and sighting apparatus of field-gun carriages or mountings, and is especially applicable to those in which there is a traversing bar or plate having at its forward end trunnions and at its other or rear end lugs for connection with the elevating-screw, a socket being provided between the said trunnions for the reception of the vertical pivot of the gun-cradle.

According to our present invention we so arrange the elevating and training gear and the sight as to allow for the simultaneous or the independent action of the gun and sight, whereby the gun may be "ranged" by a man on one side of the carriage and "pointed" by a man on the other side.

In order that our said invention may be clearly understood and readily carried into effect, we will describe the same more fully with reference to the accompanying drawings, in which—

Figures 1 and 2 are side elevations of the elevating, traversing, and sighting apparatus as seen, respectively, from the left and right hand side of the mounting. Fig. 3 is a vertical transverse section taken through the elevating and traversing gear. Fig. 4 is a vertical transverse section through the ranging-gear. Fig. 5 is a rear elevation of the sighting apparatus. Fig. 6 is a side elevation, and Fig. 7 a plan, of the traversing bar. Fig. 8 is a vertical section through the vertical pivot and the trunnions of the traversing bar. Fig. 9 is an elevation of a portion of the gear, showing a catch arrangement hereinafter described.

Like letters of reference indicate similar parts in all the figures.

A is the gun, and B the cradle in which it recoils.

C is the trail.

D is the traversing bar or plate.

E is the sight-bar.

F is the hand-wheel of the training-gear, G the hand-wheel of the gear for simultaneously elevating the gun and sighting apparatus, 60 and H the hand-wheel of the gear for elevating the gun independently of the sighting apparatus—i. e., for "ranging" the gun. The aforesaid hand-wheel G is situated on the left-hand side of the gun and the ranging hand-wheel H on the right-hand side of the gun. The said hand-wheel F of the training-gear is also situated on the left-hand side of the gun, so that the elevating and traversing of the gun for pointing can be effected from 70 the left-hand side, while the elevation of the gun independently of the sighting apparatus for ranging can be effected from the right-hand side of the gun by the hand-wheel H. The full elevation of the gun may be obtained 75 by the actuation of the ranging hand-wheel H, and the actuation of the pointing hand-wheel gives the necessary elevation or depression required for the sight. The elevating-wheel G is geared by bevel-wheels g^1 with a shaft g^2 , connected by bevel-gearing g^3 with a rotary sleeve g^4 , mounted in an oscillatory bracket G', having trunnions g^5 , supported in bearings g^6 on the trail. The said oscillatory bracket also has a screw-nut g^7 fixed thereto, 80 said nut engaging with the outer or lower one of the telescopic screws g^8 g^9 . The inner or upper screw g^7 is pivotally connected by a cross-head g^{10} with a shaft f, carrying the worm f', said shaft also engaging with lugs 90 d d' at the rear end of the traversing bar D. The said shaft f is also provided with a toothed wheel f², that gears with a corresponding toothed wheel f³ on a shaft f⁴, carrying the training or traversing hand-wheel F. The 95 worm f' gears with the toothed traversing rack or segment b, Figs. 1 and 2, which is adapted to slide on a segmental guide-piece d', forming part of the traversing bar D. This guide-piece has an elongated hole d'', 100

Figs. 6 and 7, through which the screw h of the ranging-gear extends, said screw engaging at its lower end with a screw-nut h^2 , situated below the guide-piece d and connected 5 with the said rack or segment b by bolts b^1 . The said screw h is hollow and receives a core h^3 , Fig. 4, which has lugs h^4 at its upper end by which it is pivotally connected with the gun-cradle by a hollow cross-bar h^5 . The 10 lower end of the said core h^3 has a nut h^6 , by which the screw h is kept in place without interfering with its revolution. The upper end of the screw h has a bevel-wheel h^7 , with which gears a bevel-pinion h^8 , mounted on a 15 shaft h^9 , extending through the hollow cross-bar h^5 and carrying the ranging hand-wheel H .

In connection with the ranging-gear is a large graduated disk or indicator I , on which is exhibited the range given to the gun by 20 any movement of the hand-wheel H , the rotary movement of said disk being effected by a worm h^{10} on the shaft h^9 gearing with a bevel-wheel i of the disk through the intervention of a worm-wheel and bevel-pinion. 25 (Not shown in the drawings.) Contiguous to said rotary disk is a fixed pointer or index i^x , Fig. 2, for facilitating the setting of the graduated disk to any particular graduation thereof.

The traversing bar D has the socket d^2 , Fig. 30 7, for the reception of the vertical pivot b^2 of the gun-cradle, so as to enable the lateral movement or traversing of the cradle and gun to be effected. The said traversing bar also has the trunnions $d^2 d^3$, by which it is 35 supported in the trail C for enabling it and the gun to be elevated or depressed by the actuation of the hand-wheel G . In order to allow the cradle and gun to be elevated or depressed with respect to the traversing bar 40 D when the hand-wheel H is actuated for ranging, the said socket d^2 has recesses for the reception of trunnions or an axle d^4 , which is carried by the pivot b^2 . By putting the axis of the trunnions or axle d^4 at a slight 45 angle with respect to that of the trunnions of the traversing bar, as represented in Fig. 8, we are able to give the usual permanent drift allowance to the gun, which varies in proportion to the degree of elevation given thereto.

The sighting apparatus comprises two rods $E E'$, one arranged above the other, the upper one, E' , being capable of lateral adjustment with regard to the lower one by means of a 55 pivotal connection e . On this upper bar are arranged the fore and rear sights. By imparting to the upper bar a slight traverse with respect to the lower one—i. e., with respect to the gun—allowance for drift, &c., can be 60 made. This movement may be effected in the ordinary well-known manner by a horizontal screw and a small milled-head e' . The said bar E is supported near its rear by a bracket e^2 , extending from the traversing 65 segmental rack b , and at its forward end it is pivotally connected at e^3 to a bracket or arm e^4 , carried by the training-pivot of the gun-

cradle. The pivots e and e^3 are provided with eccentric adjusting-bushes for accurately adjusting the line of sight, so that when the gun is at the horizontal position the line of sight shall be absolutely parallel to the axis of the gun.

From the arrangement hereinbefore described it will be seen that if the left-hand 75 elevating-wheel G and training-wheel F are actuated the gun may be pointed without in any way interfering with the right-hand or ranging gear, and if the right-hand wheel H is actuated the gun may be given elevation 80 suitable for the required range without interfering in any way with the sight which may have already been laid on the object by the left-hand gear. When the training-hand wheel F is in operation, the elevating-gear 85 controlled by the hand-wheel G is not in any way interfered with; but the ranging-gear and sight are caused to traverse with the gun.

We may use an arrangement for holding the traversing, elevating, and ranging hand-wheels in position when the gun is traveling or whenever it is desired to lock the hand-wheels. An arrangement for this purpose is illustrated in Fig. 9, which consists of a spring-catch J , pivoted at j to a suitable bracket j' , 90 through which the shaft of the hand-wheel passes, said catch being adapted to engage with notches j^x , formed in the boss of the hand-wheel or its shaft, thus locking it to the bracket.

What we claim, and desire to secure by Letters Patent of the United States, is—

1. In a field-gun carriage, the combination with the gun-cradle, the sight-bar and the traversing bar, of trunnions on said traversing bar connecting it with the trail, vertical and transverse pivots on the cradle supported by the traversing bar, means for turning said cradle about either of its said pivots and means for turning said traversing bar about its trunnions, substantially as and for the purpose specified.

2. In a field-gun carriage, the combination with the gun-cradle, of a traversing bar carried by the trail and adapted to turn about a horizontal axis, means for connecting the cradle to said traversing bar to permit of its turning about a vertical axis and also about a horizontal or approximately horizontal axis, a sight-bar pivotally connected with the cradle-pivot, a transversely-sliding piece carried by the traversing bar, means for supporting the rear part of the sight-bar on the transversely-sliding piece, means for adjustably supporting the rear part of the cradle from the said transversely-sliding piece and means for adjustably supporting the rear part of the traversing bar on the trail, whereby the simultaneous or independent action of the gun and sight can be effected, substantially as described.

3. In a field-gun carriage, the combination with the gun-cradle, of a traversing bar trunnioned in the trail, a vertical pivot on said

cradle fitting a socket at the forward part of the traversing bar, a transverse axle carried by the cradle-pivot, a sight-bar connected with the aforesaid cradle-pivot, means for laterally shifting the gun-cradle and sight-bar about said vertical pivot for traversing the gun, means operative from one side of the gun for shifting the traversing bar about its trunnions for simultaneously elevating the gun and sight-bar, and means operative from the opposite side of the gun for shifting the gun-cradle about the aforesaid transverse axle, independently of the sight-bar, for ranging the gun, substantially as and for the purpose specified.

4. In a field-gun carriage, the combination with the gun-cradle, of a traversing bar trunnioned in the trail, a vertical pivot on said cradle fitting a socket at the forward part of the traversing bar, a transverse axle carried by the cradle-pivot and supported in said traversing bar at an angle with respect to the axis of the trunnions for giving the permanent drift allowance to the gun, a sight-bar connected with the aforesaid cradle-pivot, means for laterally shifting the gun-cradle and sight-bar about said vertical pivot for traversing the gun, means operative from one side of the gun for shifting the traversing bar about its trunnions for simultaneously elevating the gun and sight-bar, and means operative from the opposite side of the gun for shifting the gun-cradle about the aforesaid transverse axle independently of the traversing bar, for ranging the gun, substantially as and for the purpose specified.

5. In a field-gun carriage, the combination with the gun-cradle, of a traversing bar trunnioned in the trail, a vertical pivot on said cradle fitting a socket at the forward part of the traversing bar, a transverse axle carried by said cradle-pivot, a sight-bar connected with the cradle-pivot, a segmental guide-piece on the traversing bar, a toothed segment adapted to slide on said guide-piece and carrying the ranging-gear and the rear support for the sight-bar, a worm gearing with said toothed segment and carried by the traversing bar, means independent of the ranging-gear for actuating said worm, and means for shifting the traversing bar about its trunnions substantially as described.

6. In a field-gun carriage, the combination with the gun-cradle, of a traversing bar trunnioned at its forward part in the trail, a vertical pivot on said cradle fitting a socket in

the traversing bar at a point between the said trunnions, a transverse axle carried by said cradle-pivot and supported at an angle with respect to the axis of the trunnions, a sight-bar pivotally connected with the cradle-pivot, a segmental guide-piece on the traversing bar, a toothed segment adapted to slide on said guide-piece, a worm engaging with the toothed segment and carried by the traversing bar, 60 means for actuating the worm, a screw-nut on the toothed segment, a screw engaging with said nut and pivotally connected at its upper end with the cradle, means for supporting the rear part of the sight-bar from 65 said toothed segment, means for actuating said screw, a range-indicator, means for operating said indicator simultaneously with the operation of the said screw, and means independent of said screw for shifting the 70 traversing bar about its trunnions substantially as described.

7. In a field-gun carriage, the combination with the gun-cradle, of a traversing bar trunnioned at its forward part in the trail, a vertical pivot on said cradle fitting a socket in the traversing bar at a point between the said trunnions, a transverse axle carried by said cradle-pivot and supported at an angle with respect to the axis of the trunnions, a sight-bar pivotally connected with the cradle-pivot, a segmental guide-piece on the traversing bar, a toothed segment adapted to slide on said guide-piece, a worm engaging with the toothed segment and carried by the traversing bar, 80 means for actuating the worm, a screw-nut on the toothed segment, a screw engaging with said nut and pivotally connected at its upper end with the cradle, a bracket on the toothed segment for supporting the rear part 85 of the sight-bar, means for actuating said screw, a graduated range-indicating dial, means for operating said dial simultaneously with the operation of said screw, telescopic elevating-screws one of which is connected 90 with the aforesaid traversing bar and the other with an oscillatory nut carried by the trail, and means for actuating said telescopic elevating-screws substantially as described.

In testimony whereof we have hereunto set 95 our hands, in presence of two subscribing witnesses, this 21st day of May, 1903.

ARTHUR TREVOR DAWSON.

GEORGE THOMAS BUCKHAM.
